ROTATABLE RACK FOR STORING RECORD ALBUMS OR SIMILAR ARTICLES

Donald D. Treu, Box 299, Webster City, Iowa 50595

Filed Apr. 7, 1967, Ser. No. 6,572

Term of patent 14 years

(Cl. D33—3)

FIG. 1

FIG. 3

FIG. 2

FIG. 4

FIG. 5

FIG. 1 is a perspective view of a rotatable rack for storing record albums or similar articles showing my new design;

FIG. 2 is a side elevational view looking directly at one of the partitions in FIG. 1 thereof;

FIG. 3 is a top view thereof;

FIG. 4 is a side elevational view of FIG. 1; and

FIG. 5 is a bottom view thereof.

I claim:

The ornamental design for a rotatable rack for storing record albums or similar articles, as shown.
